UNITED STATES PATENT OFFICE.

LUTHER GIFFORD, EDWARD H. SCHULTZ, AND CHARLES L. WEST, OF ST. CLOUD, MINNESOTA, SAID SCHULTZ ASSIGNOR OF HIS ENTIRE RIGHT TO WILLIAM L. SELL, OF ST. CLOUD, MINNESOTA.

AUTO HEADLIGHT.

Application filed September 25, 1923. Serial No. 664,749.

To all whom it may concern:

Be it known that we, LUTHER GIFFORD, EDWARD H. SCHULTZ, and CHARLES L. WEST, citizens of the United States, residing at St. Cloud, in the county of Stearns and State of Minnesota, have invented a new and useful Auto Headlight, of which the following is a specification.

The present invention has reference to automobile headlights, and aims to provide a novel arrangement of reflectors forming a part of a headlight, whereby the light rays from the headlight will be projected downwardly on the road surface and away from the line of vision of persons operating approaching motor vehicles.

Another object of the invention is to provide a device of this character having novel means for supporting and adjusting the reflectors to insure the proper illumination of the road surface.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a longitudinal sectional view through a head lamp of an automobile constructed in accordance with the invention.

Figure 2 is a sectional view taken on line 2-2 of Figure 1.

Referring to the drawings in detail, the reference character 5 designates the body portion of the lamp which is elongated as clearly shown by Figure 2 of the drawings, but substantially circular in vertical section.

As shown, an offset portion 6 forms a part of the body 5 in which offset portion is positioned the usual electric bulb 7 that supplies the necessary light for the lamp.

A reflector 22 forms the inner surface of the offset portion 6 and directs the light rays downwardly onto the sections 8 and 9 of the reflector.

The reflector embodies a forward section 8 and an upper curved section 9, the sec-

tion 8 being of a construction to extend across the lower portion of the lamp, and as shown has its lower forward end hingedly connected to the body portion 5 at 10, the upper end thereof extending to a point in a line with the upper edge of the opening of the body portion in which the lens 11 is positioned.

Secured to the rear surface of the reflector 8 is a bracket 12 to which the rod 13 is pivotally connected, which rod extends through an opening in the wall of the body portion where the same is threaded at 14 to receive the wing nut 15 that holds the rod in various positions of adjustment.

The curved reflector 9 extends to the rear wall of the body portion 5 and is disposed at an angle with respect to the bulb 7 so that light rays projected onto the reflector 9 will be reflected upwardly and rearwardly dissipating a portion of the light rays prior to the passage of the light rays from the lamp.

In order that the light rays will be directed only to the upper portion of the lamp, a hinged plate 16 is provided, which is hingedly connected to the body of the lamp at 17 the hinged plate resting on the curved reflector 9 to close the space between the rear end of the reflector 9 and body portion 5 when the reflectors are adjusted.

The lens 11 is held in position by a securing ring 18 which is secured by means of the screws 19, whereupon the lens may be readily and easily removed if it becomes necessary to replace the bulb 7.

Secured to the rear wall of the body portion 5 is a socket member 20 which is formed with an opening to receive the usual lamp bracket not shown, there being provided a set screw 21 for holding the lamp against movement with respect to its bracket.

From the foregoing it will be obvious that light rays projected from the bulb 7 will be directed downwardly on the reflector 8 from where they will be extended outwardly, and downwardly illuminating the road surface over which the vehicle, equipped with the lamp is moving, the light rays being projected along the line of vision of a operator of an approaching machine.

We claim:

1. A lamp of the class described including a body portion, a reflector positioned within

the body portion, said reflector having a forward end hingedly connected to one wall of the body portion, an upper curved section forming a part of the reflector and having one edge thereof normally engaging one wall of the body portion, means for moving the reflector, towards and away from the rear wall of the body portion, and means having connection with the body portion and contacting with the upper curved section of the reflector for preventing light rays from passing to the rear of the reflector.

2. A lamp of the class described including a body portion, formed with an upper offset portion providing a lamp housing, a reflector having its forward end hingedly connected to the lower front wall of the body portion and having its rear end disposed at

a point adjacent to the lamp housing, a curved reflecting surface carried at the rear end of the reflector, said curved reflecting surface adapted to reflect light rays into the lamp housing and a hinged member supported adjacent to the lamp housing and contacting with the curved surface to prevent light rays from passing to the rear of the reflector.

In testimony that we claim the foregoing as our own, we have hereto affixed our signatures.

LUTHER GIFFORD,
EDWARD H. SCHULTZ,
CHARLES L. WEST.
